TIME CLOCK CASING

George H. Kress, Newark, N.J., assignor to General Time Corporation, New York, N.Y., a corporation of Delaware

Filed Feb. 10, 1964, Ser. No. 78,566

Term of patent 14 years

(Cl. D42—7)

FIG. 1

FIG. 2

FIG. 1 is a top front perspective view of a time clock casing showing my new design;

FIG. 2 is a left-side perspective view thereof, the right side being substantially a mirror image of the left side.

The rear, not shown, is plain and unornamented.

I claim:

The ornamental design for a time clock casing, substantially as shown and described.
